(57) **CLAIM**

The ornamental design for a bag, as shown and described.

DESCRIPTION

FIG. 1 is a perspective view of a first embodiment of a bag, showing my new design;

FIG. 2 is a front view of the first embodiment;

FIG. 3 is a rear view of the first embodiment;

FIG. 4 is a right side view of the first embodiment;

FIG. 5 is a left side view of the first embodiment;

FIG. 6 is a top view of the first embodiment;

FIG. 7 is a bottom view of the first embodiment;

FIG. 8 is a perspective view of a second embodiment of a bag, showing my new design;

FIG. 9 is a front view of the second embodiment;

FIG. 10 is a rear view of the second embodiment;

FIG. 11 is a right side view of the second embodiment;

FIG. 12 is a left side view of the second embodiment;

FIG. 13 is a top view of the second embodiment; and,

FIG. 14 is a bottom view of the second embodiment.

The broken lines shown depict portions of the bag that form no part of the claimed design.

1 Claim, 10 Drawing Sheets
